(Granted under the act of March 3, 1883, as
amended April 30, 1928; 370 O. G. 757)

1

This invention relates to oscillator circuits and more particularly to circuits for generating double pulses.

There has been a need in the art for a circuit capable of generating a double pulse output, since such output may be employed in numerous instances for controlling operation of or calibrating various electrical machines. For example, the output of a double pulse generator may be utilized to measure the resolving time of an electronic counter circuit, or may be employed to operate electronic switches of the scale-of-two type in which case the time that the switch is opened or closed is dependent upon the time interval of separation of the double pulses.

It is therefore an object of the present invention to provide an oscillator circuit for generating double pulses.

Another object is to provide a double pulse generator which includes means for varying the time interval or the separation between the double pulses.

Another object is to provide a double pulse generator with means for maintaining the time interval between the double pulses constant, and including means to vary the rate of repetition of double pulses.

Another object is to provide a double pulse generator which includes a pair of non-oscillating vacuum tubes each driven by a source of saw-tooth voltage whereby each of the tubes produce a pulse upon application of each cycle of a saw-tooth voltage thereto, with means varying the time that each of said tubes produce a pulse.

Still another object of the invention is to provide a double pulse generator interconnected with an oscillograph in such a manner to indicate the double pulses whereby the time interval or separation therebetween may be accurately measured.

Still another object is to provide a double pulse generator interconnected with an oscillograph for indicating the output of the generator, with means synchronizing the output of the generator with the operation of the oscillograph with a timing wave for calibrating the double pulse pattern on the oscillograph.

Other objects and features of the invention will appear more fully from the following detailed description when considered in connection with the accompanying drawings which disclose one embodiment of the invention. It is to be expressly understood, however, that the drawings are designed for purposes of illustration only and not as a definition of the limits of the invention, ref-

2

erence for the latter purpose being had to the appended claims.

In the drawings, wherein similar reference characters denote similar parts throughout the several views:

Fig. 1 is a block diagram of a double pulse generator interconnected with an oscillograph;

Fig. 2 is a circuit diagram of the generator disclosed in Fig. 1;

Fig. 3 is a schematic showing of the voltage applied to grid 38 of tube 39 shown in Fig. 2;

Fig. 4 is a schematic showing of the voltages of grid 37 of tube 39 shown in Fig. 2, and

Fig. 5 is a diagrammatic showing of the double pulse output of the oscillator disclosed in Figs. 1 and 2.

With reference more particularly to Fig. 1 of the drawings a double pulse generator is disclosed therein including a saw-tooth wave generator 10 which simultaneously feeds saw-tooth wave forms, through buffer amplifiers 11 and 12 to pulser circuits 13 and 14. The saw-tooth wave input to pulser circuits 13 and 14 controls operation of the latter circuits in such a manner that a negative and a positive pulse is generated at the output of each of the circuits upon application of each cycle of the saw-tooth voltage thereto. The pulsating outputs of pulser circuits 13 and 14 are fed through rectifying buffer amplifiers 15 and 16 to output terminals 17 and 18 of the generator. As will appear more fully hereinafter, means are provided in pulser circuits 13 and 14 for varying the time between generation of pulses at each of the circuits, upon simultaneous application of saw-tooth wave cycles thereto, to thus vary the time interval or the separation between the double pulse output at terminals 17 and 18. Buffer amplifiers 11 and 12 function to segregate pulser circuits 13 and 14 from the saw-tooth wave generator 10 and from each other so that the outputs of the pulser circuits are completely independent of the time interval or separation between the double pulses, while rectifying buffer amplifiers 15 and 16 function to rectify and amplify the pulsating output of pulser circuits 13 and 14 to produce extremely sharp pulses of a predetermined polarity at the output of the generator.

In practically all instances of application of the double pulse generator described above, it is necessary to know the time interval or the separation between the double pulses. Means are therefore provided by the present invention for indicating the output of the double pulse generator and for properly calibrating such indication

so that the time interval between double pulses may be accurately measured. As shown in Fig. 1, the output of the double pulse generator is fed to vertical deflection plates 19 and 20 of oscillograph 21, while the sweep voltage for the oscillograph is derived directly from the output of sawtooth wave generator 10, and such voltage is applied to horizontal deflection plates 23 and 24 of the oscillograph. This arrangement obtains automatic equality of the oscillograph sweep and the double pulse frequencies as well as maintaining extreme steadiness of the oscillograph pattern. In order to calibrate the oscillograph pattern so that the time interval between double pulses produced thereon may be readily measured, a calibrated timing wave is impressed on the vertical deflection plates of the oscillograph. As shown, a timing wave generator 60, such as a calibrated beat frequency oscillator, is provided which supplies a timing wave to the vertical deflection plates of the oscillograph to superimpose a timing wave on the oscillograph pattern. In order to maintain the timing wave pattern on the oscillograph stationary with respect to the double pulse pattern, the timing wave output of generator 60 controls operation of the saw-tooth wave generator 10 to thus completely synchronize the entire system.

The circuit diagram of the double pulse generator is disclosed in Fig. 2. As shown, saw-tooth wave generator 10 comprises a relaxation oscillator which includes a thermionic gas-filled tube 25 having the plate and cathode thereof respectively connected to positive and ground potential in a conventional manner. Capacitances 27, 28 and 29, of different capacities, may be individually connected in the plate-cathode circuit of tube 25 in order to vary the frequency of generator 10. Capacitances 30 and 31 are connected to the plate of tube 25, between resistances 32 and 33, for coupling the output of saw-tooth wave generator 10 to tubes 34 and 35. When positive potential is applied through resistances 32 and 33, capacitance 28, or capacitance 27 or 28, receives an increasing charge, the value of which is determined by the value of the potential applied to the plate of tube 25, and by the value of the capacitance. As the charge of either capacitance 27, 28 or 29 builds up, the plate of tube 25 receives a corresponding potential. When the potential on the plate of tube 25 reaches a sufficient value to render the tube conducting, the potential charge of capacitance 27, 28 or 29 is discharged through tube 25 to complete generation of the saw-tooth wave form, and, as the charge decreases the potential of the plate of tube 25 likewise decreases. As the plate potential decreases to the cut-off potential of tube 25, the charge on capacitances 27, 28 or 29 again increases to generating the next saw-tooth wave form. When timing wave generator 60 is utilized, the potential of the grid of tube 25, which is normally biased negative through resistance 26, is varied in accordance with the output of generator 60 to control the time of discharge of tube 25.

The saw-tooth voltage output of generator 10 is fed to buffer amplifiers 11 and 12 each of which respectively include duplex triode vacuum tubes 34 and 35 thus providing a two-stage amplifier. The saw-tooth wave forms are thus amplified and applied to control grids 36 and 37 of pulser tubes 38 and 39 respectively. Tubes 38 and 39 are thermionic gas-filled tubes and are connected in pulser circuits 13 and 14 in such a manner to

prevent generation of oscillations therein but to allow the tubes to operate in a self-quenching condition. In order to achieve the foregoing, resistances 40 and 41, of large value, are respectively connected in the plate circuit of tubes 38 and 39 to limit the discharge current therefrom, while large values of negative direct-current bias are applied to grids 36 and 37 through potentiometers 42 and 43. Since equal positive potentials are applied to the plates of tubes 38 and 39, equal cut-off potentials are established at each of the tubes, and the tubes are therefore rendered conducting when a potential is applied to the grids thereof that corresponds to the above mentioned cut-off potentials. By applying the necessary negative direct-current potential to grids 36 and 37 to cause the saw-tooth voltages from amplifiers 11 and 12 to swing across the cut-off potentials of each of the tubes, the tubes will be blocked and rendered conducting upon application of each cycle of the saw-tooth voltage. This may be more readily understood with reference to Fig. 3, wherein the input voltages to grid 36 are diagrammatically shown. As disclosed, the cut-off potential of tube 38 is established by the positive potential applied to the plate thereof, while the negative direct-current bias on grid 36 is varied by means of potentiometer 42 to cause the saw-tooth voltage to swing across the line representing the cut-off potential. When the saw-tooth wave sweeps, thus driving grid 36 more negative, the saw-tooth wave form will cross the line of cut-off potential at point *a* thus quenching tube 38. As the saw-tooth wave continues to sweep, the tube will remain non-conducting until the saw-tooth wave again crosses the line of cut-off potential at point *b*. Tube 38 then remains in a conducting state for the completion of the cycle of the saw-tooth wave and until the subsequent saw-tooth wave cycle passes the line of cut-off potential at *a* to thus again quench the tube. It is to be expressly understood, therefore, that for application of each cycle of the saw-tooth voltage, tube 38 is quenched and then rendered conducting, and therefore the tube generates a positive and a negative pulse upon application of each cycle of the saw-tooth voltage. Since it is desired to obtain output pulses of minimum width, the pulses generated during the time that the tube 38 is rendered conducting are utilized, since it has been found that the quenching period of the tube is substantially greater than the striking time thereof.

As mentioned heretofore, one of the objects of the present invention is to provide a double pulse generator including means for varying the time interval or the separation between the double pulse. Such means comprises potentiometers 42 and 43 which are adapted to control the negative direct current bias on grids 36 and 37 in such a manner that, upon simultaneous application of a cycle of saw-tooth voltage thereto the tubes will be quenched and rendered conducting at different instances during movement of the saw-tooth wave cycle to thus generate negative pulses at different instances. As shown in Fig. 3, since the saw-tooth voltages vary with respect to the line of cut-off potential upon variation of the negative direct current bias on grid 36, the instant that tube 38 is rendered conducting, with respect to the movement of each cycle of saw-tooth wave voltage, may be readily varied. Therefore, by applying unequal values of negative direct current bias to grids 36 and 37 tubes 38 and 39 are, upon application of every cycle of the saw tooth volt-

age, rendered conducting at different instances. In Fig. 4, the input voltages to grid 37 are diagrammatically shown, with the line representing the cut-off potential of tube 38 corresponding to the cut-off potential of tube 38 as shown in Fig. 3. By considering Figs. 3 and 4 together, it can be readily seen that the saw-tooth voltages are simultaneously applied to grids 36 and 37 and that the negative direct current bias on grid 37 is a value greater than the bias on grid 36. The saw-tooth voltages applied to grid 37 are thus caused to cross the line of cut-off potential at higher points on the saw-tooth waves than the line of cut-off potential is crossed by the saw-tooth waves shown in Fig. 3. Therefore, the tubes are quenched at approximately the same time since the wave-form of each saw-tooth cycle is substantially vertical when the current is moving more negative, and tube 38 is rendered conducting prior to tube 39 since the line of cut-off potential of tube 38 is crossed by the saw-tooth wave during the period when the latter is becoming less negative, before a similar action occurs at tube 39. The foregoing means thus provides a very accurate method of varying the time interval or the separation between the double pulse output of the generator.

Buffer amplifiers 11 and 12 not only provide suitable amplification and the proper number of phase shifts of the saw-tooth voltage output of generator 10, but, as stated heretofore, completely isolate tubes 38 and 39 from generator 10 and from each other to prevent interaction between the tubes. When potentiometers 42 and 43 are adjusted in such a manner that the separation between the pulse outputs of the tubes is extremely small, a few microseconds for example, the grid current drawn by one tube upon generation of a pulse would immediately drive the other tube conducting, thus reducing the time interval to zero in the event buffer amplifiers 11 and 12 were not provided.

As stated heretofore, when tubes 38 and 39 are rendered conducting, a negative pulse is generated at the outputs thereof and such pulses are utilized for the output pulses of the generator. When the tubes are rendered conducting negative pulses are generated instantaneously, followed by a substantially slower rise to normal potential and therefore it becomes necessary, in order to obtain sharp pulses, to amplify the high frequency components of these pulses and provide means for rejecting the low frequency components thereof. Such means are included in rectifying buffer amplifiers 15 and 16 each of which comprise a two-stage amplifier having a high transductance tube in each stage. Amplifier 15 comprising tubes 44 and 45, while tubes 46 and 47 are included in amplifier 16. In order to obtain high frequency response of each of the tubes of the amplifiers suitable inductances are included in the plate circuits of each of the tubes. As shown, inductances 48 and 49 are respectively included in plate circuits of tubes 44 and 45 while inductances 50 and 51 are included in similar circuits associated with tubes 46 and 47. By utilizing high transconductance tubes in each stage of amplifiers 15 and 16 the necessary gain is obtained to provide sharp pulses without substantially increasing the pulse width. By suitably selecting the values of inductances 48, 49, 50 and 51, and the values of resistances 52 associated with each of the inductances, a large range of pulse widths and amplitudes, within certain limits, may be obtained. Amplifiers 15 and 16 are biased in such

a manner to only amplify the negative pulses generated by tubes 38 and 39, and potentiometers 53 and 54 are included therein for controlling the amplitude of the pulses. A negative double pulse output is thus obtained at terminals 17 and 18, as disclosed in Fig. 5 of the drawings. The separation of time interval T between the pulses may be readily varied by operation of potentiometers 42 and 43 in a manner noted heretofore.

- 10 When the circuit shown in Fig. 2 is utilized in connection with oscillograph 21 in a manner disclosed in Fig. 1, the output of timing wave generator 60 is fed to output terminal 17 by way of connection controlled by switch 55, thus synchronizing the double pulse output of the generator with the saw-tooth voltages supplied from generator 10. The sweep voltage for the oscillograph is derived from the relaxation oscillator comprising tube 25, by a connection from the plate thereof which includes capacitance 56. Capacitance 56 functions to couple the saw-tooth output of generator 10 to the oscillograph to thus simultaneously apply saw-tooth wave forms thereto at a rate controlled by the output of generator 60. When tubes 38 and 39 are rendered conducting, grid current is drawn by these tubes which in turn distorts the saw-tooth wave form of the relaxation oscillator. Buffer amplifying tubes 34 and 35, positioned between the relaxation oscillator and the pulser tubes, prevent such distortion of the output wave form of the relaxation oscillator and consequently prevent a simultaneous distortion of the pulse pattern of the oscillograph.
- 15 30 There is thus provided by the present invention a novel oscillator circuit for generating double pulses which includes means for maintaining a predetermined time interval or separation between the pulses. Moreover, means are provided for varying such time interval so that an extremely small separation, of a few microseconds, is maintained between the pulses, or for varying such time interval so that a substantially greater separation is obtained. The circuit is of such construction that extremely sharp pulses of substantially narrow width are provided at the output thereof and so that the pulses may be supplied to a suitable indicator, such as an oscillograph, whereon a pattern of the pulses may be obtained simultaneously with a synchronizing wave whereby the separation may be accurately measured.

40 45 50 55 The invention described herein may be manufactured and used by or for the Government of the United States of America for governmental purposes without the payment of any royalties thereon or therefor.

What is claimed is:

1. A circuit for generating double pulses comprising a pair of electron discharge devices each having a plate, a cathode and a control electrode, means applying equal positive potentials to said plates whereby equal cut-off potentials are established at each of said devices, means simultaneously applying saw-tooth voltages to each of said control electrodes, and means applying direct current potentials to each of said control electrodes to cause the saw-tooth voltages to swing across said cut-off potentials whereby each of said devices is rendered conducting and quenched upon application of each cycle of said saw-tooth voltages.

2. A circuit for generating double pulses comprising a pair of electron discharge devices each having a plate, a cathode and a control electrode,

means applying equal positive potentials to said plates whereby equal cut-off potentials are established at each of said devices, means simultaneously applying saw-tooth voltages to each of said control electrodes and means applying direct current potentials to each of said control electrodes to cause the saw-tooth voltages to swing across said cut-off potentials whereby each of said devices is rendered conducting and self-quenched upon application of each cycle of said saw-tooth voltages, the direct current potential to one of said electrodes being less than the direct current potential to the other electrode for rendering one of said devices conducting before the other device.

3. A circuit for generating double pulses comprising a pair of electron discharge devices each having a plate, a cathode and a control electrode, means applying equal positive potentials to said plates whereby equal cut-off potentials are established at each of said devices, means simultaneously applying saw-tooth voltages to each of said control electrodes, means applying direct current potentials to each of said control electrodes to cause the saw-tooth voltages to swing across said cut-off potentials whereby each of said devices is rendered conducting and self-quenched upon application of each cycle of said saw-tooth voltages, and means producing a variation in the direct current potential to said control electrodes for rendering one of said devices conducting before the other device.

4. A double pulse generator comprising a pair of electron discharge devices each having a plate, a cathode and at least one control electrode, means applying equal positive potential to each of said plates for establishing equal cut-off potentials at each of said devices, means simultaneously applying saw-tooth voltages to each of said control electrodes, means applying direct current potential to each of said control electrodes for causing the saw-tooth voltages to swing across said cut-off potentials whereby each of said devices is cut-off and rendered conducting and quenched upon application of each cycle of said saw-tooth voltages, and means varying the direct current potential applied to said control electrodes for varying the time that the said devices are rendered conducting.

5. A double pulse generator comprising a pair of electron discharge devices each having a plate, a cathode and a control electrode, means applying equal positive potential to said plates for establishing equal cut-off potentials at each of said devices, means simultaneously applying saw-tooth voltages to each of said control electrodes in the same phase relation, means applying negative potential to each of said control electrodes for causing said saw-tooth voltages to swing across said cut-off potentials whereby each of said devices is rendered conducting and quenched upon application of each cycle of said saw-tooth voltages, and means varying the negative potentials applied to said control electrodes with respect to each other for causing the saw-tooth voltages to cross said cut-off potentials at different points whereby the devices are rendered conducting at different instances.

6. A double pulse generator comprising a oscillator for generating saw-tooth wave forms, a pair of non-oscillating electron discharge devices each having a plate, a cathode and a control electrode, means applying equal positive potentials to each of said plates for establishing equal cut-off potentials at each of said devices, means simultane-

ously applying said saw-tooth wave forms to the control electrodes for controlling said devices, and means applying negative bias to said control electrodes for causing said saw-tooth wave forms to swing across said cut-off potentials whereby each of said devices are quenched and then rendered conducting upon application of every cycle of said saw-tooth wave forms.

7. A double pulse generator comprising a oscillator for generating saw-tooth wave forms, a pair of non-oscillating electron discharge devices each having a plate, a cathode and a control electrode, means applying equal positive potentials to each of said plates for establishing equal cut-off potentials at each of said devices, means simultaneously applying said saw-tooth wave forms to the control electrodes for controlling said devices, means applying negative bias to said control electrodes for causing said saw-tooth wave forms to swing across said cut-off potentials whereby each of said devices are quenched and then rendered conducting upon application of every cycle of said saw-tooth wave forms, and means varying the negative bias applied to said control electrode for causing the devices to be rendered conducting at different times.

8. A double pulse generator comprising a relaxation oscillator for generating saw-tooth wave forms, a pair of non-oscillating electron discharge devices each having a plate, a cathode and a control electrode, means applying equal positive potentials to each of said plates for establishing equal cut-off potentials at each of said devices, means simultaneously applying said saw-tooth wave forms to the control electrodes for controlling said devices, means isolating each of said devices from the other, means applying negative bias to said control electrodes for causing said saw-tooth wave forms to swing across said cut-off potentials whereby each of said devices are quenched and then rendered conducting upon application of every cycle of said saw-tooth wave forms, and means varying the negative bias applied to said control electrode for causing the devices to be rendered conducting at different times.

9. A double pulse generator comprising a relaxation oscillator for generating saw-tooth wave forms, a pair of non-oscillating electron discharge devices each having a plate, a cathode and a control electrode, means applying equal positive potentials to each of said plates for establishing equal cut-off potentials at each of said devices, means simultaneously applying said saw-tooth wave forms to the control electrodes for controlling said devices, means applying negative bias to said control electrodes for causing said saw-tooth wave forms to swing across said cut-off potentials whereby each of said devices are quenched and then rendered conducting upon application of every cycle of said saw-tooth wave forms, means varying the negative bias applied to said control electrode for causing the devices to be rendered conducting at different times, and a pair of buffer amplifier means positioned between said oscillator and each of said devices for preventing interaction between the devices.

10. A double pulse generator comprising a relaxation oscillator for generating saw-tooth wave forms, a pair of electron discharge devices each having a plate, a cathode and a control electrode, means applying equal positive potential to each of said plates for establishing equal cut-off potentials at each of said devices, means simul-

taneously applying said saw-tooth wave forms to each of said control electrodes in the same phase, means applying negative bias to each of said control electrodes for causing said saw-tooth wave forms to swing across said cut-off potentials whereby each of said devices is quenched and rendered conducting upon application of every cycle of said saw-tooth wave forms to generate a positive and a negative impulse at the output of each of said devices, means varying the negative bias to each of said control electrodes for causing the devices to be rendered conducting at different instants, and means rectifying the output of each of said devices to obtain impulses of a predetermined polarity.

11. A double pulse generator comprising a relaxation oscillator for generating saw-tooth wave forms, a pair of electron discharge devices each having a plate, a cathode and a control electrode, means applying equal positive potential to each of said plates for establishing equal cut-off potentials at each of said devices, means simultaneously applying said saw-tooth wave forms to each of said control electrodes in the same phase, means positioned between said oscillator and each of said devices for preventing interaction between the devices, means applying negative bias to each of said control electrodes for causing said saw-tooth wave forms to swing across said cut-off potentials whereby each of said devices is quenched and rendered conducting upon application of every cycle of said saw-tooth wave forms to generate a positive and a negative impulse at the output of each of said devices, means varying the negative bias to each of said control electrodes for causing the devices to be rendered conducting at different instants, and means rectifying the output of each of said devices to obtain impulses of a predetermined polarity.

12. In an apparatus of the class described, an oscillograph, a saw-tooth wave generator, means driven by said generator for producing double pulses upon application of a unidirectional portion of said saw-tooth wave thereto, means applying the double pulses to a pair of deflection plates of said oscillograph, and means applying the output of said generator to another pair of deflection plates of said oscillograph.

13. In an apparatus of the class, described an oscillograph, a relaxation oscillator for generating saw-tooth waves, a timing wave generator for controlling said oscillator, means driven by said saw-tooth waves for generating double pulses upon application of a unidirectional portion of said saw-tooth waves thereto, means applying said double pulses to a pair of deflection plates of said oscillograph, means applying the output of said oscillator to another pair of deflection plates of said oscillograph, and means passing the output of said generator to said one pair of deflection plates.

14. In an apparatus of the class described, an oscillograph, a saw-tooth wave generator, means driven by said generator for producing double pulses upon application of every cycle of said saw-tooth waves thereto, means varying the time interval between said double pulses, means applying the double pulses to a pair of deflection plates of said oscillograph for producing said double

pulses on the screen of said oscillograph whereby said time interval may be readily determined.

15. An apparatus of the class described comprising an oscillograph, a relaxation oscillator for generating saw-tooth voltage, a timing wave generator controlling said oscillator, means driven by said oscillator for generating double pulses upon application of every cycle of said saw-tooth voltage thereto, means establishing a time interval between said double pulses, means applying said double pulses to one pair of deflection plates of said oscillograph, means applying the output of said oscillator to another pair of deflection plates of said oscillograph for producing a pattern of the double pulses on the screen of the oscillograph, and means applying the output of said generator to said one pair of deflection plates for synchronizing said double pulses on the screen of said oscillograph whereby said time interval may be determined.

16. An apparatus of the class described comprising an oscillograph, a relaxation oscillator for generating saw tooth voltages, a timing wave generator controlling said oscillator, means driven by said oscillator for generating double pulses upon application of every cycle of said saw tooth voltage thereto, means establishing a time interval between said double pulses, means varying said time interval, means applying said double pulses to one pair of deflection plates of said oscillograph, means applying the output of said oscillator to another pair of deflection plates of said oscillograph for producing a double pulse pattern on the screen of the oscillograph, and means applying the output of said generator to said one pair of deflection plates for synchronizing the double pulse pattern on the screen of said oscillograph with said timing wave whereby said time interval may be accurately measured.

17. A circuit for generating double pulses comprising a pair of electron discharge devices each having a plate, a cathode and a control electrode, means applying definite positive potentials to said plates whereby definite cut-off potentials are established at each of said devices, means simultaneously applying saw-tooth voltages to each of said control electrodes to cause the saw-tooth voltages to swing across said cut-off potentials whereby each of said devices is rendered connecting and quenched upon application of each cycle of said saw-tooth voltages.

18. A circuit for generating double pulses comprising a pair of electron discharge devices each having a plate electrode, a cathode and a control electrode, means applying positive potentials to said plates, means applying direct current negative bias potentials to said control electrodes to render the said devices self-quenching, means simultaneously applying a saw-tooth voltage to both said control electrodes whereby each of said devices is rendered conducting and quenched upon application of each cycle of said saw-tooth voltage, and means varying one of the said potentials as applied to one of said devices to vary the amount of change in control-electrode potential by said saw-tooth voltage necessary to render the said one device conducting.

HAROLD LIPSCHUTZ.
